2,113,809

APPARATUS FOR DEWAXING HYDRO-CARBON OILS

Bert H. Lincoln, Ponca City, Okla., assignor to
 Continental Oil Company, Ponca City, Okla.,
 a corporation of Delaware

Application February 21, 1936, Serial No. 65,089

2 Claims. (Cl. 196—19)

My invention relates to a method and apparatus for dewaxing hydrocarbon oils, and more particularly to a method employing a photoelectric control.

In the operation of a dewaxing process employing centrifugal separation of precipitated wax, it is not possible by diluting and chilling stocks of oil bearing wax to consistently dewax to a certain prescribed cold test. In the operation of the dewaxing system there is apparently considerable wax held on the chilling coils which will fall off after a certain weight has been piled up, giving a very high concentration of wax at the centrifugal separators. The centrifugal separators are designed and equipped for separating precipitated wax from a solution of oil in varying percentages between certain prescribed and definite limits.

When a solution of greater wax content than that for which the machine is designed is charged to a centrifugal separator, complete separation is not always obtained. When this occurs, the discharge from the wax-free oil outlet of the machine is hazy or cloudy, the amount of cloud depending upon the wax content. The wax-free oil which has passed through the machine satisfactorily, will in such cases be contaminated by oil which is not wax-free or properly dewaxed.

One object of my invention is to provide a method and apparatus in which improperly dewaxed oil is prevented from contaminating a bulk of dewaxed oil solution which has been properly dewaxed.

Other and further objects of my invention will appear from the following description.

In the accompanying drawings which form part of the instant specification and which are to be read in conjunction therewith, and in which like numerals are used to indicate like parts in the various views:

Fig. 1 is a diagrammatic view of a dewaxing system embodying one modification of the apparatus of my invention and adapted to carry out the process of my invention.

Fig. 2 is a diagrammatic view of the electrical connections of the apparatus shown in Fig. 1.

A wax bearing oil suitably diluted with a diluent is charged through line 1 from any suitable source and passes through heat exchangers 2 and 3, in heat exchange with chilled dewaxed oil solution on its way to storage tank 4. The partially cooled oil solution leaves heat exchanger 3 through line 5 and passes through heat exchangers 6 and 7 in heat exchange with a cold medium, which may be chilled brine, passing from a refrigeration system,

shown diagrammatically at 8, through line 9. The cooling medium leaves heat exchanger 7 through line 10 and passes back to the refrigeration system for recycling. The further chilled oil solution leaves heat exchanger 7 through line 11, and passes through heat exchangers 12 and 13 in heat exchange with a refrigerant adapted to chill the oil solution to a low temperature, as for example —50° F. The refrigerant may be ammonia, for example, or any gas adapted to be compressed by compressor 14, pass through heat exchanger 15, from which the cool compressed refrigerant leaves through line 16 to be expanded through valve 17, through the heat exchangers 12 and 13 for refrigerating the wax bearing oil solution. The chilling of the oil solution to a low temperature precipitates the wax out of solution. In appearance the solution is cloudy or hazy, the haze being caused by small wax particles. These wax particles are of greater gravity than the solution in which they are suspended. This permits a separation to be made by centrifugal force. The solution bearing precipitated wax leaves heat exchanger 13 through line 18 and passes into a manifold 19, from which it is withdrawn through a series of pipes, 20, 21, 22 and 23, controlled by valves 24, 25, 26 and 27. While I have shown four centrifuges, it is to be understood that any suitable number may be employed. One plant, for example, may employ thirty-six centrifuges. One or more chilling tanks may be placed in line 18 if necessary.

The valves 24, 25, 26 and 27 are urged to closed position by springs, and are normally held in open position by the action of electro-magnets. The control mechanism is contained in housings 28, 29, 30 and 31. The oil passing through the pipes 20, 21, 22 and 23, enters the respective bowls of centrifuges 32, 33, 34 and 35. The centrifuges are driven by electric motors 36, 37, 38 and 39, which are controlled by electro-magnetic operated switches contained in housings 40, 41, 42 and 43. The valve controls 28, 29, 30 and 31 and the motor controls 40, 41, 42 and 43, are governed by photoelectric relays contained in housings 44, 45, 46 and 47.

In the diagrammatic view of Fig. 1, only the outlet for the dewaxed oil solution is shown, and appears as pipes 48, 49, 50 and 51. These pipes pass through jackets 52, through which a refrigerating medium is passed through lines 53, leaving jackets 52 through lines 54. The dewaxed oil solution passes from heat exchangers 52, through lines 55, which pass into a common manifold 56. Interposed in lines 55 are fittings 55

51 fitted with windows adapted to pass a beam of light from light sources in suitable housings 58, as can readily be seen by reference to Fig. 2. The dewaxed oil solution passes from manifold 56 through line 59 through heat exchangers 2 and 3 to storage tank 4.

Referring now to Fig. 2, an incandescent lamp 60 is lighted by current furnished through conductors 61 and 62. A beam of light 68 passes through windows 63 and 64 provided in fitting 57, upon photoelectric tube 65 having a cathode 66, and an anode 67. Main line wires 68 and 69 are connected to an alternating current supply. The primary 70 of a transformer is connected across the main line. The primary is provided with three secondaries 71, 72 and 73. The secondary 71 is connected at one end to the anode 67 of the photoelectric tube 65 and at the other end to one side of a condenser 74, the other side 20 of which is connected to the cathode 66 by a conductor 75. The secondary 72 is connected across the filament 76 of a triode 77. The center tap of secondary 72 is connected to the arm 78 of a potentiometer provided with a resistance 79, and 25 is adapted to adjust the bias upon the photoelectric tube 65, and to one end of the secondary 73 through conductor 80. Secondary 73 is in the plate circuit of the triode 77 in series with electromagnets 81 and 82 of relays controlling the 30 switch 40 of the motor 36, and the electro-magnet, controlling valve 24, in housing 28.

A condenser 83 for by-passing high frequency currents is shunted across relay coils 81 and 82. The output of photoelectric tube 65 is impressed 35 upon the grid 90 of triode 77 through conductor 91 and resistance 92.

In operation, as long as the dewaxed oil solution passing through fitting 57 is clear of haze or cloud, the light beam 68 will pass through the oil 40 solution in sufficient intensity so that the plate current of triode 77 is able to magnetize electromagnets 81 and 82 to attract armatures 93 and 94, to close the circuit across contact points 95 and 96, and 97 and 98 respectively. The closing 45 of the circuit across contacts 95 and 96 actuates the motor switch within the housing 40 to start the motor 36. The closing of the circuit across contact points 97 and 98 actuates the electro-magnet in housing 28 against the action of a 50 spring to open valve 24. As long as the oil solution is clear the motor will be running and the valve 24 will remain open. It will be obvious, of course, that in starting with no oil solution in pipe 55 no resistance to the passage of light beam 55 68 is encountered, and the condition described will take place.

When the oil leaving the centrifuge 32 becomes clouded, a resistance to the passage of light will occur, which will reduce the light beam in intensity. When this occurs the output of photoelectric tube 65 will drop making the grid less positive, thus reducing the plate current, demagnetizing to an extent electro-magnets 81 and 82 and permitting springs 99 and 100 to pull armatures 93 and 94 to a position breaking the circuit across contact points 95 and 96, and 97 and

98, respectively, thus shutting off the motor 36 and closing valve 24.

The value at which this action will take place can be adjusted by adjusting the position of arm 78 upon potentiometer 79 and varying the bias 5 upon the anode of the photoelectric tube 65. In practice I have found that an undissolved wax content of from .01 to .2 of 1 percent or more by weight will be sufficient to give satisfactory manipulation of the photoelectric relay.

It will be observed that I have accomplished the objects of my invention. A centrifuge plant might produce 5,000 barrels of wax-free oil over a period of time, and the entire production may be ruined by an hour's unsuccessful operation by 15 a single centrifuge. It is impossible to determine by laboratory tests the condition of the operation of the centrifuge in a period of less than 1½ to 2 hours, and by the use of my invention I preclude the possibility of ruining a batch of dewaxed oil 20 solution by the faulty operation of one or more centrifuge machines. It is of importance that the oil solution passing through the fitting 57 be of approximately the same low temperature as it leaves the centrifuge so that the presence of wax 25 will appear in the form of a haze. It is for this reason I provide chilling jackets 52. The small amount of haze in oil will disappear when the temperature is allowed to rise.

It will be understood that my invention may 30 be employed on any separator of wax regardless of solvent or means of separation, provided the unseparated wax appears as a haze in the oil-solvent. For example, certain heavy halogenated solvents are used in dewaxing oils by centrifugal 35 force and my control method is applicable to these pressures. My equipment may also be used on a wax press separator.

It will be understood that certain features and sub-combinations are of utility and may be employed without reference to other features and sub-combinations. This is contemplated by and is within the scope of my claims. It is further obvious that various changes may be made in details within the scope of my claims without departing from the spirit of my invention. It is therefore, to be understood that my invention is not to be limited to the specific details shown and described.

Having thus described my invention, what I 50 claim is:

1. In a dewaxing apparatus a centrifuge for separating precipitated wax from an oil solution, a line for conducting oil solution containing precipitated wax to said centrifuge, a valve controlling said line, a motor for driving said centrifuge, an eduction line from said centrifuge for withdrawing dewaxed oil solution and means responsive to the transparency of the dewaxed oil solution leaving the centrifuge for controlling said 60 valve and said motor.

2. A dewaxing apparatus as in claim 1 wherein said eduction line is provided with heat exchange means for chilling the dewaxed oil solution leaving said centrifuge.

BERT H. LINCOLN.
